(57) **CLAIM**

The ornamental design for a fluid management connector, as shown and described.

DESCRIPTION

FIG. 1 is a perspective view of a fluid management connector showing my new design;

FIG. 2 is a right side view of our new design, the left side view being identical thereof;

FIG. 3 is a front view of our new design, the rear view being identical thereof;

FIG. 4 is a bottom view of our new design; and,

FIG. 5 is a top view of our new design.

The broken line portions of FIGS. 4-5 are for illustrative purposes only and form no part of the claimed design.
